UNITED STATES PATENT OFFICE.

HAYWOOD WASHINGTON GRAY, OF ADEL, GEORGIA.

BOAT-PROPELLER.

Specification of Letters Patent. Patented Feb. 19, 1918.

1,256,551.

Application filed October 10, 1916. Serial No. 124,845.

To all whom it may concern:

Be it known that I, HAYWOOD W. GRAY, a citizen of the United States, residing at Adel, in the county of Berrien and State of Georgia, have invented certain new and useful Improvements in Boat-Propellers; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in boat propellers adapted to be attached to the stern or side of the boat and so constructed as to be reversible.

The invention consists of a simple and efficient apparatus of this nature, having various details of construction, combinations and arrangements of parts which will be hereinafter fully described, shown in the accompanying drawings and then specifically defined in the appended claims.

My invention is illustrated in the accompanying drawings, in which:—

Figure 1 is a top plan view of the propeller showing the parts in dotted lines in different positions.

Fig. 2 is a vertical sectional view on line 2—2 of Fig. 1.

Fig. 3 is a sectional view on line 3—3 of Fig. 1.

Fig. 4 is an enlarged detail plan view of a part of the invention.

Fig. 5 is a detail plan view showing the parts illustrated in Fig. 4, in different relative positions.

Reference now being had to the details of the drawings by numerals, 1 designates the frame of the apparatus which may be of any size or shape and so arranged that it may be lowered into the water or raised therefrom and held at different positions. Mounted to have reciprocating movements in openings 2 in the cross-piece 3 of the frame are the beams 4, 5, 6 and 7, the rear ends of the beams 4 and 7 being pivotally connected to

the outer ends of the levers 8 which are slotted at 9 and their inner ends are pivotally connected to the pivots 10, which latter are carried by a cross-piece 11 which is fastened to corresponding ends of the beams 5 and 6.

A pitman, designated by numeral 12, is adapted to be pivotally connected to the cross-piece 11 and is reciprocated by any

suitable power mechanism, not shown. The ends of said beams have attached thereto respectively the racks 13, 14, 15 and 16, each of which is provided with axially rocking shafts 17 and 17* mounted in apertures in the top and bottom portions of the racks, the upper ends of the shafts projecting above the upper ends of the racks for a purpose which will be presently described. Each of said shafts has a propelling blade 18 secured thereto which is designed to feather when being moved through the water in one direction. All of the racks have similarly constructed blades 70 and it will be noted that the two racks 13 and 16 move forward or backward together, while the other racks 14 and 15 move together in a direction opposite from the movements of the racks 13 and 16. 75

Mounted upon said frame is a longitudinally movable bar 19, having angular grooves 20 formed in one face thereof which receive the angular projections 21 upon the brackets 22, and serve as means to guide the bar 19 as it is moved longitudinally. Cam members, designated respectively by numerals 23 and 24, project from the bar 19 in pairs, there being two of said cam members and each rack carrying two blades. Opposite each pair of cam members 23 and 24 are reversely arranged cam projections 25 and 26 which are fastened to a bar 27, grooved on its outer face, at 28, to receive the angular projections 29 upon the arms 30 which are secured to the frame. 85

It will be noted upon reference to the drawings that each shaft 17 in the various racks is provided with an angled crank pin 31 which has pivotal connection with a plate 95 32, and 33 designates a similar crank pin which is fastened to the shaft 17* and is pivotally connected also to the plate 32. A pin 34 projects from each rack and is adapted to engage one or another of the notches 100 34* formed in the edge of a plate 32 and serving to hold the plate in place while the apparatus is in operation.

In order to impart a longitudinal movement to the two bars 19 and 27, a rock shaft 105 35 is journaled upon the frame and has links 36 pivotally connecting the same, one with each of said bars, and 38 is a handle fixed to the rock shaft and forming means for rocking the same accordingly as it may 110 be desired to cause the apparatus to propel a boat forward or backward, the said rock shaft and longitudinally movable bars with attachments forming a reverse mechanism.

In operation, the apparatus being lowered into the water, either at the stern or at one side or another of the boat, it may be held at different elevations so that the blades 5 will dip partially or wholly within the water, it being understood that, when the blades are immersed to their farthest extent, the maximum power may be obtained. As the pitman causes the beams to reciprocate, the intermediate beams 5 and 6 will move in a direction opposite to the movements of the beams 4 and 7. Assuming that the apparatus is adjusted to propel the boat forward, the propeller blades carried by the two racks 14 and 15, which, at the moment the apparatus begins to operate, are at their farthest forward limits, will be positioned broadside to the water against which they are to be pushed as the shafts 5 and 6 are moved longitudinally toward the rear of the apparatus. When the two racks 14 and 15 approach their farthest rearward limit, a crank pin 17^a carried by a shaft 17^b will come against the curved edge of the cam projection 23 and cause the blades to feather on their return forward movements, the two blades being caused to turn in unison through the medium of the plates 32. As the two racks upon the beams 5 and 6 move rearward, the other racks 13 and 16 upon the beams 4 and 7 respectively will move forward, the blades carried by the racks 13 and 16 feathering while the blades on the intermediate racks are being forced rearward and vice versa. When it is desired to reverse the propelling apparatus, the operator by causing the shaft 35 to rock may throw the bars 27 and 19 in proper position so that, when the crank pins 17^a upon the shaft 17 come in contact with the curved edges of the cam projections 24, the propelling blades will operate in a reverse manner to their movements when in positions to propel the craft forward.

What I claim to be new is:—

1. In a hydraulic propelling apparatus for boats comprising a frame, reciprocating beams mounted therein, a rack fixed to each beam, a rock shaft journaled in each rack, a blade upon each rock shaft, movable reversing bars, cam projections thereon, a crank pin carried by each rock shaft and adapted to contact with a cam projection, and connections between the shafts.
2. In a hydraulic propelling apparatus for boats comprising a frame, reciprocating beams mounted therein, a rack fixed to each beam, a plurality of rock shafts journaled in each rack, a blade upon each rock shaft, movable reversing bars, cam projections thereon, a crank pin carried by each rock shaft and adapted to contact with a cam

projection, plates pivotally connecting the rock shafts of each rack to cause the same to rock together.

3. In a hydraulic propelling apparatus for boats comprising a frame, reciprocating beams mounted therein, a rack fixed to each beam, a plurality of rock shafts journaled in each rack, a blade upon each rock shaft, longitudinally movable bars, each having a groove in the face thereof, means upon the frame engaging said grooves, cam projections upon the bars, crank pins fixed one to each rock shaft, pivotal connections between the rock shafts of each rack to cause the same to rock together, and means for moving the longitudinal bars.

4. In a hydraulic propelling apparatus for boats comprising a frame, reciprocating beams mounted therein, a rack fixed to each beam, a plurality of rock shafts journaled in each rack, a blade upon each rock shaft, longitudinally movable bars, each having a groove in the face thereof, means upon the frame engaging said grooves, cam projections upon the bars, crank pins fixed one to each rock shaft, pivotal connections between the rock shafts of each rack to cause the same to rock together, a rock shaft journaled in the frame and having pivotal link connections with said movable bars.

5. In a hydraulic propelling apparatus for boats comprising a frame, reciprocating beams mounted therein, a rack fixed to each beam, a plurality of rock shafts journaled in each rack, a blade upon each rock shaft, movable reversing bars, cam projections thereon, crank pins secured to said rock shafts, a plate having pivotal connections with the rock shafts in each rack, notches upon the edge of said plate, a pin projecting from each rack adapted to engage said notches, and means for moving the reversing bars.

6. In a hydraulic propelling apparatus for boats comprising a frame, racks and longitudinal beams secured thereto, propelling blades carried by the racks, a cross-piece connecting the intermediate of said beams, levers pivoted upon the frame and at their outer ends to the outermost of the side beams and the inner ends of said levers pivotally connected to said cross-piece, a pitman pivotally connected to the cross-piece, and means for feathering the blades when moving in one direction.

In testimony whereof I hereunto affix my signature in presence of two witnesses.
